HAIR CURLER

Jacob Goodman, Brooklyn, N. Y., assignor to
Delamere Company, Inc., a corporation of
Delaware

Application August 3, 1935, Serial No. 34,522

3 Claims. (Cl. 132—41)

This invention relates to hair curlers and more particularly to improvements in that type of curler which is intended to be retained in the hair until the curl has been formed.

5 An object of my invention is to provide a hair curler of generally soft pliable construction so that it may be comfortably worn in the hair even during sleep or while resting the head on a pillow.

10 A further object is to provide a device of this type with means for gripping the ends of the hair prior to rolling the hair into a curl.

Another object is to provide a curler which is simple and inexpensive to manufacture, and easy 15 to manipulate.

With these and other objects in view, the invention consists in the novel features of construction and arrangement of parts hereinafter described and illustrated in the accompanying drawing, in which:—

20 Figure 1 is a side view of my improved hair curler partly broken away, and showing the hair ends clamped in full lines in one position, and in dot-and-dash lines in another;

25 Fig. 2 is a top plan view thereof showing ends of hair gripped in the clamp prior to rolling the hair into a curl;

Fig. 3 is a view of the device showing the hair rolled thereon;

30 Fig. 4 is an enlarged sectional view showing the pivoted connection of the clamp to the tube;

Fig. 5 is a similar view showing a modification of the pivotal connection; and

Fig. 6 is a sectional view of a modified form of 35 the device.

Referring now to the drawing, 10 indicates a soft pliable tube, preferably made of rubber, around which the hair to be formed into a curl may be wound. An elastic cord 11 extends outwardly from one end of the tube and has a tip 12 at its free end. The other end of the cord 11 is secured to the tube in any suitable manner, as, for instance, by means of the staple 13.

Extending lengthwise over the tube 10 is a 40 clamp 14. This clamp grips the ends of the hair 15 onto the tube prior to rolling the hair into a curl. After the hair has been rolled, the elastic cord 11 is stretched over the roll and the tip 12 is inserted in the open end of the tube so as to 45 retain the device in the hair.

In the form of the invention shown in Figs. 1, 2 and 4, the clamp has ears 16 which extend on opposite sides of the tube at one end and are perforated for reception of the pin 17 to provide a pivotal connection of the clamp to the tube.

5 In the form of device shown in Fig. 5, the ears of the clamp are formed with integral inwardly extending lugs 18 which are, in this instance, used to provide the pivotal connection instead of the pin 17.

10 Fig. 6 illustrates a further modification of the device wherein a spring clamp 19 is employed instead of the pivoted clamp 14 previously described. The spring clamp consists of a piece of metal bent in substantially U-shape, having one leg 20 of the U inserted in the tube 10, and having the other leg 21 lying lengthwise over the tube. The leg 20 may be secured to the tube by means of the staple fastening 22 as shown, or in any other suitable manner. In this form of 15 the device the ends of the hair are clamped between the tube and the leg 21 of the spring clamp prior to rolling the hair into a curl.

20 What I claim is:—

1. A hair curler comprising a soft rubber tube 25 having a laterally compressible wall and a hollow bore, a clamp extending lengthwise of the tube, and an elastic cord fastened at one end of the tube and having a tip at its free end which is insertable in the opposite end of the tube when the cord is stretched lengthwise over the tube.

30 2. A hair curler comprising a soft rubber tube having a laterally compressible wall and a hollow bore, a clamp pivotally mounted on the tube and extending lengthwise thereof, and an elastic cord fastened at one end of the tube and having a tip at its free end which is insertable in the opposite 35 end of the tube when the cord is stretched lengthwise over the tube.

3. A hair curler comprising a soft rubber tube 40 having a laterally compressible wall and a hollow bore, a spring clamp extending lengthwise of the tube, and an elastic cord fastened at one end of the tube and having a tip at its free end which is insertable in the opposite end of the tube when the cord is stretched lengthwise over the 45 tube.
